UNITED STATES PATENT OFFICE.

OTTMAR MERGENTHALER, OF BALTIMORE, MARYLAND, ASSIGNOR TO THE
OTT. MERGENTHALER COMPANY, OF SAME PLACE.

AUTOMATIC MILLING-MACHINE.

SPECIFICATION forming part of Letters Patent No. 636,917, dated November 14, 1899.

Application filed May 12, 1898. Serial No. 680,503. (No model.)

To all whom it may concern:

Be it known that I, OTTMAR MERGENTHALER, a citizen of the United States, residing at Baltimore, in the State of Maryland, have 5 invented certain new and useful Improvements in Automatic Milling-Machines, of which the following is a specification.

My invention relates to automatic milling-machines, and especially to that class of automatic milling-machines wherein it is designed to act upon the two opposite sides of the work in a single operation of the machine.

Although it will be understood that my improved machine is capable of general application wherever it may be desired to operate upon a series of blanks, it is shown and described herein as employed in connection with the manufacture of matrices for use in linotype-machines—such, for example, as those shown and described in Letters Patent of the United States Nos. 436,531 and 436,532, granted to me on the 16th day of September, 1890.

25 In my improved machine I have provided means whereby the work is tightly held and clamped upon a suitably-actuated reciprocating slide or table, which in its movement in one direction carries the work past and in contact with a suitably-actuated cutting mechanism, whereby one side of the work is operated upon, and which in its return movement carries the work past and in contact with the same cutting mechanism, the position of which, however, has been so changed and shifted as to cause it to act upon the other side of the work. I have further provided suitable means for effecting the reciprocation of the slide or table and for changing the position of the cutting mechanism and for locking it securely in its adjusted positions. I have also provided suitable mechanism for effecting the automatic throw-out of the cam-shaft at the end of a complete reciprocal 40 operation of the feed-slide, together with other novel and useful devices adapted for employment in my improved machine.

My invention, then, consists in the novel construction and combination of parts herein- 45 after to be described in the specification and finally pointed out in the claims.

Referring now to the drawings, Figure 1 is a top plan view of my improved milling-machine. Fig. 2 is a right-hand side view of the machine. Fig. 3 is a vertical sectional view 55 of a portion of the machine, taken substantially on the section-line 3 3 in Fig. 2. Fig. 4 is a vertical sectional view of the machine, taken substantially on the line 4 4 in Fig. 1. Fig. 5 is a detached sectional view showing 60 the mode of action of the cutter upon the work. Fig. 6 is a detached detail view showing the special form of chuck or work-holder employed.

The frame A of the machine is or may be 65 of any suitable form or construction, provided only that it possesses strength and rigidity to sustain the operating parts. The frame A is provided with a suitable guideway A², upon which the feed slide or table F is 70 adapted to reciprocate, and also with the brackets A' A' for retaining the slide F in position.

Power is imparted to the machine by the customary fast and loose pulleys B' upon the 75 main shaft B of the machine. Also fast upon the main shaft B is the driven pinion B², which gears into and turns the pinion K and also the worm-screw B³, which gears into and turns the worm-gear B⁴. The worm-gear B⁴ is fast 80 upon and imparts motion to the shaft B⁶, carrying the worm-screw B⁷, which in turn gears into and turns the worm-gear B⁸, fast upon the cam-shaft C, thereby imparting motion thereto. The shaft B⁶ is journaled at one end 85 in the pivotal bearing B⁵, which is supported upon the shaft B in such manner as to be capable of turning thereon, and at the other end is journaled in the pivotal bearing B¹⁰ in the arm D, which is fast upon the rock-shaft D². 90 Also attached to the rock-shaft D² is the arm D', which is connected by means of the spring D⁴ to the frame A in such manner that the normal tendency of the spring D⁴ will be to turn the rock-shaft D², thereby raising the 95 bearing B¹⁰ of the shaft B⁶ and turning the bearing B⁵ about the shaft B in such manner that the worm-screw B⁷ is lifted out of engagement with the worm-gear B⁸, thereby stopping the rotation of the cam-shaft C. In 100 order to overcome the tendency of the spring D⁴ to lift the worm-screw B⁷ out of engage-

ment with the worm-gear B^8 , I have provided an arm E , fast upon the rock-shaft E^2 , suitably journaled in the frame of the machine, and having at its other end an arm or trigger E^3 , the function of which will be hereinafter described. The spring E' , attached to the arm E and to the main frame, normally tends to draw the arm E outward and into contact with the pin D^5 on the arm D . Attached to the outer end of the rock-shaft D^2 is the handle D^3 , whereby the rock-shaft D^2 may be turned in such manner as to act against the spring D^4 and to lower the worm-screw B^7 into engagement with the worm-gear B^8 , at which time the spring E' , acting on the arm E , will cause the latter to engage the pin D^5 on the arm D , thereby securing the arm D , shaft B^6 , and worm-screw B^7 in operative position. Through the parts thus described it will be seen that a continuous rotation of the cam-shaft C will be secured until the arm E is freed from engagement with the pin D^5 , which is effected in the reciprocation of the feed slide or table F by the pin F' on said slide or table coming into contact with the arm or trigger E^3 , thereby permitting the spring D^4 to raise the worm-screw B^7 and to stop the rotation of the cam-shaft C in the manner previously described.

The pinion B^2 , as previously described, gears into and turns the pinion K , which is loose upon the rock shaft or rod K' , the pinion K in turn meshing into and imparting motion to the gear L , fast upon the cutter-spindle L' . The cutter-spindle L' carries the cutters L^2 and is suitably journaled in the frame L^3 , which is supported upon the rock-shaft K' in such manner as to be capable of a partial rotation therewith and to permit of the shifting of the cutters L^2 from one operative position to the other. Also attached to the rock-shaft K' are the two arms M and M' , set angularly with relation to each other, and whereby the rock-shaft K' and the cutter-spindle L' and cutters L^2 may be locked in their several operative positions. The cam-shaft C carries the cutter-shifting cam I , and the worm-gear B^8 is provided with the cam-pieces H H , which control the locking and unlocking of the arms M and M' . The cam I effects the shifting of the cutters L^2 from one operative position to the other by reason of its contact with the roller L^4 , carried on the cutter-support L^3 , and is so shaped and timed as to raise and lower the cutters L^2 after each longitudinal movement of the feed slide or table F . To effect the locking of the cutter-frame L^3 and of the cutters L^2 in their adjusted positions by means of the locking-arms M and M' on the rock-shaft K' , as previously described, I employ the locking-detent M^2 . The detent M^2 is fast upon the rock-shaft M^3 , which is suitably journaled in the bearing M^4 , and which also carries the arm M^5 , provided with the roller M^6 , adapted to be acted upon by the cam-pieces H H on the gear B^8 . Also attached to the arm M^5 are the cord M^9 and

weight M^8 , so arranged that the arm M^5 will be normally held in its lowermost position, thereby causing the detent M^2 to engage with and firmly hold one or other of the arms M and M' . It will be apparent that when the arm M is engaged and held by the detent M^2 the cutter-frame L^3 , the spindle L' , and the cutters L^2 will be firmly held in their uppermost operative position and that when the arm M' is engaged and held by the detent M^2 the cutter-frame L^3 , spindle L' , and cutter L^2 will be firmly held in their lowermost operative position. The cam-pieces H H are so shaped and located upon the gear B^8 that during the rotation of the cam-shaft C the arm M^5 will be lifted against the force of the weight M^8 , thereby releasing the arm M or M' at the proper time to permit of the shifting of the cutter-frame L^3 , spindle L' , and cutters L^2 .

As shown on the drawings, the feed slide or table F is so formed as to be suitably guided and held upon the guideway A^2 of the frame A . The slide or table F is provided at its upper surface with the piece F^2 , which may be adjustably secured throughout the length of the slide or table F by means of the set-screws F^3 F^4 . The piece F^2 is adapted to receive and firmly retain the chuck or work-holder G by means of the set-screws F^4 F^4 . The work-holder or chuck G is shown in detail in Fig. 6 and is provided with the separable part G' , attached to the main portion G by the bolts or screws G^2 , and with the retaining-screw G^3 , whereby the work may be firmly held and retained. In practice I have found that the detachable chuck or work-holder G may be employed with great advantage and with a considerable saving of time, as in the various milling operations which are necessary in the manufacture of the matrices above referred to I am enabled to clamp the work securely in position in the chuck or work-holder, which may be placed in one machine after another without removing the work therefrom.

The feed of the slide or table F is effected and controlled by the cam J upon the cam-shaft C in the following manner: Pivotally attached to the slide or table F is the link J' , connected to the lever J^2 , pivoted to the frame of the machine. The lever J^2 is provided with the roller J^3 , so placed as to be acted upon by the cam J . Also attached to the slide or table F is the cord N , which passes over the pulley N' to a weight. (Not shown.) The action of the weight and the cord N upon the slide or table F normally tends to advance the slide or table F . This action is, however, resisted and controlled by means of the parts previously described, the cam J being so shaped and timed, as clearly shown in the drawings, as to effect the longitudinal reciprocation of the slide or table F , and consequently of the work carried thereby.

Having now described the construction and arrangement of the various parts of my improved machine, their operation will be un-

derstood to proceed in the following manner: The blanks X or other work having been previously placed or confined within the chuck or work-holder G, the latter is firmly secured 5 at the proper point upon the table or slide F. The handle D³ is then raised in such manner as to bring the worm-screw B⁷ into engagement with the worm-gear B⁸ upon the cam-shaft C, in which position the parts are held 10 by the engagement of the spring-actuated arm E with the pin D⁵ upon the arm D. Motion being imparted to the machine, the cutters are suitably actuated and the table F is fed or reciprocated by means of the parts previously 15 described in such manner as to bring the blanks or work X past and in contact with the cutters L², which at this period of the operation of the machine are held securely in their uppermost position by reason of the 20 engagement of the detent M² with the arm M. After the work X has been carried past the cutters L² the outward movement of the slide or table ceases, and due to the configuration of the cam J its return movement begins. 25 At this point of the operation one of the cam-pieces H upon the gear B⁸ comes into contact with the roller M⁶ upon the arm M⁵, thereby raising the arm M⁵ against the force of the weight M⁸ and retracting the detent M², thereby 30 unlocking the arm M. Then the cam I in the course of its rotation permits the lowering of the cutter-frame L³, thereby bringing the spindle L' and cutters L² into their lowermost operative position. At this point the roller M⁶ passes over and out of engagement 35 with the cam-piece H and the pull of the weight M⁸ advances the detent M² in such manner as to cause it to engage with and lock the arm M', thereby firmly holding the cutters L² in their lowermost operative position. 40 The return movement of the slide or table F continues, bringing the work-holder G and the work X a second time into contact with the cutters L², but upon the side of the work 45 opposite that encountered by the cutters during the first traverse of the slide or table F. When the table F has about reached its outermost position, the pin F' carried thereby contacts with the trigger-arm E³, turning the 50 rock-shaft E² and tripping the arm E, thereby releasing the arm D and permitting the spring D⁴ to lift the worm-screw B⁷ out of engagement with the worm-gear B⁸, thereby 55 stopping the operation of the cam-shaft. The work-holder is then removed from the slide or table F and fresh work substituted therefor, when the operation may be repeated, as described. Fig. 5 clearly shows the manner 60 in which the cutters L² act upon the work X in its lowermost position, it being apparent that an exactly identical operation of the cutters L² upon the work X, but upon the opposite side of the work X, will be obtained therefrom when the cutters L² are in their 65 elevated position.

It will be obvious that many changes may be made in the details of the invention above

described without departing from the spirit of my invention. Thus the number, character, and location of the cutters may be varied 70 and other substantially equivalent operating devices for the various parts may be substituted, all of which changes would be substantially comprised within the scope of my invention, which has been shown and described merely in a preferred form. Similarly it will be obvious that the machine is adapted to operate either upon gangs of blanks in the work-holder G, or solid work 75 may be inserted therein, as desired. 80

Having thus described the construction and operation of my invention, what I claim, and desire to secure by Letters Patent of the United States, is as follows:

1. In a milling-machine, the combination 85 of a reciprocating slide, and means for securing the work thereto, of means for holding the cutter in one position as the slide moves in one direction, and means for shifting the cutter as the slide is reversed and holding it 90 in a second position as the slide moves in the reverse direction, whereby the cutter is adapted to operate on two separate parts of the work.

2. In a milling-machine, the combination 95 of a reciprocating slide, and means for securing the work thereto, of a suitably-operated cutter, automatic means for shifting the cutter from one side of the work to the other, and automatic means for stopping the movement of the slide after it has made a complete reciprocation and the cutters have operated on both sides of the work.

3. In a milling-machine, the combination of 105 suitably-actuated cutting mechanism with means for automatically shifting the cutting mechanism to a plurality of operative positions, and means for securing and locking the same in the various operative positions, substantially as described. 110

4. In a milling-machine, the combination with suitably-actuated cutting mechanism, and automatic means for shifting the cutting mechanism to a plurality of operative positions, and automatic means for locking the 115 same in its various adjusted positions, of suitably-actuated feeding mechanism for carrying the work past and in contact with the cutting mechanism, substantially as described.

5. In a milling-machine, the combination 120 with suitably-actuated cutting mechanism, means for shifting the same to a plurality of operative positions, and means for locking the same in the various adjusted positions, of suitably-actuated feeding devices for causing the 125 reciprocation of the work in opposite directions past and in contact with the cutting mechanism, substantially as described.

6. In a milling-machine, the combination 130 with a movable frame and a cutter and arbor mounted on said frame, of a reciprocating work-table and means for rocking the frame to shift the cutter at each reversal of the movement of the table, whereby the cutter operates

upon different parts of the work as the table moves in different directions, substantially as described.

7. In a milling-machine, the combination with a reciprocating work-holder, a cutter, and means for shifting the same as the work-holder reciprocates whereby the cutter is caused to operate on different parts of the work, of mechanism for reciprocating the work-holder, automatic means for throwing said mechanism out of operation, and manually-operated means for starting said mechanism, substantially as described.

8. In a milling-machine, the combination with a reciprocating work-holder, of a vibrating frame, a suitably-actuated cutter mounted in said frame, a cam-shaft, cams on said shaft arranged to reciprocate the work-holder and periodically shift the cutter-carrying frame, and a locking device actuated by said cam-shaft and arranged to lock the cutter-frame to hold the cutter in its different operative positions.

9. In a milling-machine, the combination with a reciprocating work-holder, a vibrating frame, and a suitably-actuated cutter carried by said frame, of a cam-shaft having a connection for reciprocating the work-holder, a cam for adjusting the cutter to one side of the work as the work-holder moves in one direction and to the opposite side of the work as the work-holder moves in the opposite direction, a lock for holding said cutter in different positions comprising a pair of arms connected with the vibrating frame and a lever for interlocking the said arms, and cams on said cam-shaft adapted to operate said locking-lever to lock and unlock the cutter at proper intervals, substantially as described.

In testimony whereof I affix my signature in presence of two witnesses.

OTT. MERGENTHALER.
